UNITED STATES PATENT OFFICE.

CHARLES WILLMS, OF BALTIMORE, MARYLAND.

WATER-TANK.

No. 838,601.

Specification of Letters Patent.

Patented Dec. 18, 1906.

Application filed March 13, 1906. Serial No. 305,751.

To all whom it may concern:

Be it known that I, CHARLES WILLMS, a citizen of the United States, residing in the city of Baltimore, State of Maryland, have 5 invented certain new and useful Improvements in Water-Tanks, of which the following is a specification.

My invention relates especially to water-tanks of the class used in connection with 10 water-closets or urinals. Such tanks have heretofore usually been made of cast metal, which are bulky, cumbersome, and unattractive in appearance, or of wood lined with sheet metal, which are not durable or always 15 sanitary, as the varnished wood often becomes stained, or if the metal lining leaks the wood absorbs water.

The object of my invention is to provide a light durable tank that may be manufactured 20 economically, may be kept perfectly clean, and which will at all times present an attractive appearance.

The furniture and fittings in bath-rooms and other toilet-rooms are now to a very 25 large extent enameled, the advantages of which are well known; but the tanks are now almost universally made of wood. I have devised a tank constructed of metal and enameled which possesses in addition to the 30 usual requisites the advantages incident to enameled ware.

In carrying out my invention I form the water-containing tank of thin sheet metal and enamel it or cover it inside and out with 35 vitreous enamel. Such a tank possesses the advantages above named, but is apt to "sweat"—i. e., moisture will condense on its exterior and will either drop or run down on the walls or objects below it or in the case of 40 low-down tanks will be rubbed off by occupants of the water-closet. For this reason I provide what I call a "condensation-collector," which is also enameled and receives and delivers such water of condensation to 45 the closet-bowl.

The condensation-collector is arranged a suitable distance from the tank in order to leave an air-space around it to thus prevent condensation on the outside of the collector. 50 Couplings are employed for clamping the tank to the condensation-collector, and the inlet-pipe and the discharge-pipe are connected with these couplings. A branch pipe extends from the flush-water-discharge pipe 55 to the condensation-collector and conveys

therefrom any water which accumulates therein. Preferably water overflows from the tank through openings in the upper portion thereof or over the top, the usual overflow-pipe being thus dispensed with, and the 60 afterflow-water is conveyed by a pipe from the ball-cock to the space between the tank and the condensation-collector and flows out through the branch pipe of the flush-water-discharge pipe above referred to. 65

Other features of the invention will be hereinafter more particularly described.

In the accompanying drawings, Figure 1 is a perspective view of a low-down flushing-tank embodying my improvements. Fig. 2 70 is a perspective view of the cover of the tank detached. Fig. 3 is a perspective view of the tank with the cover removed looking from the rear. Fig. 4 is a bottom plan view of the cover. Fig. 5 shows a transverse section of 75 the cover on the line 5 5 of Fig. 4. Fig. 6 is a detail view in perspective, showing particularly how the cover is fitted to the condensation-collector and how it is secured thereto. Fig. 7 shows a vertical transverse section 80 through the water-containing tank and illustrates particularly how the flush-valve-operating lever is connected therewith. Fig. 8 is a view, on an enlarged scale and in section, showing how the water-containing tank is 85 enameled. Fig. 9 shows on enlarged scale and in vertical section the water-containing tank, the condensation-collector and cover assembled, and it also shows the mechanism within the tank for supplying water thereto 90 and discharging it therefrom. Fig. 10 is a view in perspective and on an enlarged scale of the connection between the discharge-pipe 95 of the water-containing tank and the condensation-collector whereby the water of condensation, water overflowing from the water-containing tank, and the afterflow-water may be conveyed from the condensation-collector to the discharge-pipe. Fig. 11 is a top plan view of one of the couplings employed for connecting the condensation-collector with its outlet-pipe. 100

The water-containing tank A is preferably made from a single piece of sheet metal, such as sheet-steel, and without seam. The rim 105 a is formed in the manner clearly shown in Figs. 7 and 8 by bending the material outwardly and downwardly and causing the bent-over portion of the metal to stand out from the body portion of the tank, a space a' 110

- being left between the bent-over portion and the body of the tank, which is of such size that enamel can enter it and completely cover the inside of the rim, as well as the tank-body 5 opposite the rim, and this can be done without producing bubbles or forming air-holes, all the parts of the metal of which the tank is made being completely covered and without flaws. It will be observed that there are 10 no sharp corners in the tank, and hence there is no liability of the metal cracking while being bent into shape.
- A hole is made at a^2 in the front wall of the tank to receive a bolt B, which supports the 15 valve-operating lever C. This bolt is shown as being formed with a hub or collar c, on which the lever pivots. It has a head c' at its inner end to hold the lever in place, and a metal washer c² and a soft washer c³ are in- 20 terposed between the collar c and the body of the tank, the soft washer being employed to prevent injury to the enamel. On its outer end the bolt B is provided with a nut b, a soft washer b' being interposed between the 25 nut and the body of the tank. The essential part of this portion of the apparatus is in providing a short support for the valve-operating lever, which is clamped securely to one side of the tank, there being no parts extending 30 entirely across the tank, as is often the case. Holes a³ are also preferably formed near the top of the tank near its right-hand front portion to provide an overflow, although these holes may be omitted, because 35 if there be any overflow it may be over the upper edge of the tank. The holes a² and a³, above referred to, are of course made in the tank before it is enameled, the enameling being so produced as to not completely close 40 the holes. Holes are also formed in the bottom of the tank to accommodate the couplings which connect the flush-water-discharge pipe and the inlet-pipe for the ball-cock. These will be hereinafter mentioned.
- 45 The condensation-collector D is in this instance shown as being formed as a jacket completely inclosing the water-tank. It is preferably made from a single piece of sheet metal, such as sheet-steel, without seam. It 50 has a rim d, comprising an outwardly-projecting flange at the front and at opposite ends. There are no sharp corners in the condensation-collector. These are all rounded, and the front and opposite ends are curved, as clearly shown in the drawings. The flange 55 or rim d is in like manner curved at front and at opposite ends correspondingly with the shape of the collector. At the back there is an inwardly-projecting flange at d' in order 60 to allow the collector to be made perfectly flat and even at the back, so that it may lie against the wall to which it is secured. The rear portion of the collector is preferably left open, as shown at D', to provide for ventilation and also to enable one to reach under the

water-tank when it is being lowered to secure the collector, if desired. Holes d² are formed in the flange d at its opposite rear corners to receive screws F, that attach the cover to the collector, and holes d³ are formed in the collector near its upper end and on opposite sides to provide for ventilation in case the fenestrum or opening D' is too tightly closed when the tank is attached to a wall.

d⁴ indicates keyhole-openings to receive 75 the supports for the tank.

The cover E is preferably formed of a single piece of sheet metal and enameled throughout. The body portion or top is preferably concavo-convex, as illustrated, and its edge 80 at the back is straight, as indicated at e'. At the two opposite ends and in front the edge of the cover is turned downward and inward, as indicated most clearly in Figs. 6 and 9, to form a rim e, which is somewhat U- 85 shaped in cross-section and is adapted to fit over the flange d of the collector D, being curved correspondingly therewith. It will be observed that the flange e is not bent so much at its ends, as indicated at e², the flange 90 being somewhat straightened in these portions. By this arrangement the cover may be slid horizontally over the condensation-collector and the curved portion of the flange made to embrace and interlock with the 95 flange d. Holes e³ are formed in the cover at its opposite rear corners to receive the screws F. When the cover is in place on the collector, nuts or threaded plates f are placed beneath the holes d² in the flange d, and then 100 the screws F are inserted through the holes e³. The nuts are held from turning as they lie against the body of the collector, and the screws may be tightly driven. In this way the cover may be easily held in place by means 105 of two screws only. In view of the curved configuration of the condensation-collector and the cover the latter may be more quickly replaced or removed than if the interlocking flanges were straight throughout.

110 Fig. 9 shows the water-containing tank surrounded by the condensation-collector, which in this case forms a jacket. The cover E is also shown in position.

115 It will be observed that there is an air-space X all around the water-containing tank. There is never much water in the collector, and so this air-space prevents the occurrence of condensation on the exterior of the collector. It will be observed that there 120 is no metallic connection between the upper edge of the water-containing tank and the collector, and therefore, although the water-containing tank may become very cold, the collector does not assume the same temperature on account of the air-space at all times present between the tank and the collector.

125 The water-containing tank A is connected directly with a discharge-pipe G, which communicates with the closet-bowl. The coup-

ling devices which connect the tank with the discharge-pipe are clamped both to the bottom of the tank and to the condensation-collector. The coupling member H has a relatively flat inner end *h* and is provided with a seat *h'* for the valve I, which connects with the valve-lever C. This valve-lever is connected to a rod J, in turn connected to a button or handle K, and operates in the usual way. The valve-rod *i* may be provided with suitable guides; but they are omitted in the drawings, as they form no part of the present invention. The coupling member H extends through the space X, and through the bottom of the condensation-collector D it is screw-threaded, as shown, and receives a nut L, on opposite sides of which are soft washers *l*. The nut serves not only to clamp the coupling to the bottom of the water-containing tank, but also as a spacing device to hold the condensation-collector at a proper distance from the tank, while the soft washers prevent injury to the enamel. On the outside of the condensation-collector the coupling member H receives a nut M, between which and the bottom of the collector is interposed a soft washer *m*. The nut M may also contain a soft washer *m'* to prevent leakage. By this arrangement the discharge-pipe G is connected with the water-containing tank, the condensation-collector is held a proper distance from the tank, a seat for the flushing-valve is provided, all leakage is prevented, and no injury occurs to the enamel in assembling the parts.

The inlet-valve or ball-cock N is of usual construction and operates in the usual way. Water passes from the valve at *n* into the tank, and it passes through a pipe *n'* over the top of the tank and down into the space between the tank and the condensation-collector. As is well understood, while water is flowing into the tank it also flows through the pipe *n'*, so that water may be supplied to the bowl after the flush-water has stopped running. After the tank has filled—that is, after the float O has risen to its full extent, as indicated in the drawings—the passage of water through *n* and *n'* ceases. In other constructions when a pipe similar to *n'* is used said pipe delivers into an overflow-pipe within the tank; but in my construction the pipe *n'* delivers into a collector surrounding the tank, the usual overflow-pipe being dispensed with. The pipe *n'*, it will be observed, delivers into the collector at a point removed from the opening D' or the opening where the button K is located, so that there can be no danger of water splashing to the outside.

The inlet-valve or ball-cock N is secured to the tank and collector in a manner similar to the way in which the overflow-pipe is secured. The construction is clearly indicated and need not be described; but the devices

also serve to hold the tank and collector a suitable distance apart to provide the surrounding air-space X.

The water of condensation dropping from the outside of the water-containing tank, the overflow-water passing through the openings *a*³ or over the top of the tank, and the after-flow-water delivered by the pipe *n'* collect on the bottom of the condensation-collector and immediately pass therefrom, never rising to a high level. It passes through a pipe or connection Q, which is made somewhat flexible or adjustable in order that there may be no strain on the parts when they are being assembled. Preferably the pipe Q is itself rigid and nickel-plated, as usual, and the lower end of the pipe is connected with the discharge-pipe G by a slip-joint *q*. This joint, as shown, contains a soft washer *q'* and is of such character that the pipe Q may be moved back and forth or turned in any direction while the parts are being connected; but when the nut *q'* is screwed home a secure water-tight joint is effected. At its upper end the pipe Q is connected with the collector in the following manner: A coupling R is formed on its upper end with a flanged head *r*, which projects beyond the hole in the collector, through which the coupling extends. This flange is formed with recesses *r'*, preferably four being employed, as shown in Fig. 11, and these recesses extend from the bore of the coupling to the outside of the flange, thereby bringing the upper end of the discharge-opening on a level with the bottom of the collector. In this way water received by the collector is completely drained from it. The coupling extends into a union-nut S, provided with a soft washer *s*, and this nut serves to connect the pipe Q with the coupling. A nut T is employed for clamping the coupling on the collector, a soft washer *t* being preferably interposed between the nut T and the collector to prevent it from cracking the enamel.

While I preferably connect the condensation-collector with the discharge-pipe in the manner above stated, so far as some features of my invention are concerned the pipe Q need not be connected to the discharge-pipe G in the precise manner shown. It may be connected in other ways; but its lower end should be connected in such way as not to allow sewer-gas to rise through it.

It will thus be seen that by my present improvements the water-containing tank, the condensation-collector, and the cover may be easily made and thoroughly enamelled and that the parts may be readily assembled.

The tank when discharging or flushing the closet operates in the usual way. No water from the tank passes into the condensation-collector, but while flushing with full force and under pressure flows directly into

the closet-bowl. The connection Q is always open, it contains no valve of any kind, and is free from all obstruction. Its capacity is sufficient to immediately carry off any water 5 that passes to the condensation-collector, whether it be from condensation, overflow, or afterflow from the pipe n' or whether water accumulates from all three of these sources at once.

10 I have described my invention as embodied in apparatus which I have found to be entirely practicable and which is the best way now known to me of carrying out my invention. Some parts may be used in connection 15 with other parts differing in construction from those herein illustrated and described.

I do not herein claim, broadly, a flush-tank in combination with a case in which it is contained and from which it is slightly separated 20 and a flush - pipe opening independently into each of said case and tank elements, nor a flush-tank within a case, the case being constructed to take the overflow from the tank, and a flush-pipe in communication 25 with the case and opening into the tank, as such subject-matter is claimed in my earlier applications, Serial No. 273,929, filed August 12, 1905, and Serial No. 286,002, filed November 6, 1905.

30 The novel features of my invention are herein separately specified, and what I claim is—

1. A jacket for a water-containing tank, having a curved front portion, an outwardly-projecting curved flange at the front and at 35 opposite ends, an inwardly-projecting flange at the back and a cover formed without a flange at the back but having a downwardly-projecting curved flange at the front and at 40 opposite ends adapted to embrace the flange on the jacket, substantially as described.

2. A jacket for a water-containing tank having a curved front portion, an outwardly-projecting curved flange at the front and at 45 opposite ends and a cover formed without a flange at the back but having a downwardly-projecting curved flange at the front and at opposite ends adapted to embrace the flange on the jacket, said flange on the cover being 50 curved inwardly to a greater extent at the front portion than at the rear ends thereof.

3. A jacket for a water-containing tank, formed with a curved front portion having an outwardly-projecting flange at the front and at 55 opposite ends and a cover having a concavo-convex top and formed without a flange at the back but having a downwardly-projecting curved flange at the front and at opposite sides adapted to embrace the flange 60 on the jacket, and devices for securing the cover to the jacket applied to the opposite rear ends of the cover and to the opposite rear ends of the outwardly-projecting flange of the jacket.

4. A jacket for a water-tank formed of a

single piece of sheet metal and enameled, provided with an opening or fenestrum at the back and with ventilating-openings at the side and an enameled cover detachably connected with the jacket. 70

5. The combination of a water-tank, a jacket surrounding it, means for supporting the tank within the jacket and holding it in such position therein as to provide an air-space around the tank, an inlet-valve for admitting water to the tank, a pipe extending from the inlet-valve into the jacket for conveying afterflow-water from the inlet-valve to the jacket, and an outlet from the jacket, substantially as described. 75 80

6. The combination of a water-tank, a jacket surrounding it, an outlet-pipe extending through the jacket and into the water-tank whereby water flows directly from the water-tank without first passing into the 85 jacket, a separate outlet-passage from the jacket, means for admitting water to the interior of the tank and a pipe conveying water from the inlet-valve to the jacket outside the tank. 90

7. The combination of a water-tank containing overflow-openings, a jacket surrounding the tank, means for holding the jacket a suitable distance from the tank to provide an air-space surrounding the tank, a discharge-pipe conveying water directly from the tank without first passing through the jacket, and a separate discharge-passage from the jacket whereby overflow-water or water of condensation is conveyed from the 10 jacket. 95

8. The combination of a water-tank, a condensation-collector associated therewith, a discharge-pipe for conveying flush-water from the tank through the condensation-collector, clamping devices which connect said discharge-pipe with both the tank and the condensation-collector, a discharge-pipe for the condensation-collector and means for clamping said pipe thereto. 11

9. The combination of a water-tank, a condensation-collector associated therewith, a discharge-pipe for conveying the flush-water from the tank, coupling devices clamped to the tank and to the condensation-collector and to which said discharge-pipe is connected, and a branch pipe extending from said discharge-pipe and connected with the bottom of the condensation-collector for conveying water therefrom. 11

10. The combination of a water-tank, a condensation-collector associated therewith, pipe-couplings clamped to the condensation-collector and the tank and which serve to hold the tank and collector a suitable distance apart, a discharge-pipe connected with said couplings and conveying flush-water from the tank, a rigid branch pipe adjustably connected with said discharge-pipe and adjustable connections between the opposite 12 13

end of the branch pipe and the bottom of the condensation-collector.

11. The combination of a water-tank having openings in the bottom for the discharge and inlet couplings, a condensation-collector associated with the tank and having also openings for the discharge and inlet couplings, a discharge-pipe clamped to both the condensation-collector and the tank, an inlet-valve clamped to both the condensation-collector and the tank, and a branch pipe from the discharge-pipe connected with the bottom of the condensation-collector and conveying water therefrom.

12. The combination with the condensation-collector, of a discharge-pipe and couplings for attaching the pipe thereto formed with a head arranged inside the collector and

having a recess, the bottom of which is close to the bottom of the collector whereby all water can be drained therefrom.

13. The combination of a water-tank, a condensation-collector associated therewith and held a suitable distance therefrom to provide an air-space, a discharge-pipe connected directly with the tank and conveying water therefrom, a discharge-pipe for the collector and a coupling for clamping it to the collector having recesses the bottoms of which are close to the bottom of the tank.

In testimony whereof I have hereunto subscribed my name.

CHARLES WILLMS.
